UNITED STATES PATENT OFFICE.

DAVID COGHILL, OF TORONTO, ONTARIO, CANADA, ASSIGNOR OF ONE-HALF TO THOMAS M. GIBSON, OF TORONTO, CANADA.

ATTACHMENT TO SEWING-MACHINES.

998,956.

Specification of Letters Patent. Patented July 25, 1911.

Application filed November 23, 1909. Serial No. 529,570.

To all whom it may concern:

Be it known that I, DAVID COGHILL, a subject of the King of Great Britain, residing at Toronto, in the county of York and Province of Ontario, Canada, have invented a new and useful Attachment for Sewing-Machines, of which the following is a specification.

My invention relates to a device adapted 10 to be attached to any ordinary machine, or a sewing machine adapted for special work such as corset or fancy sewing, whereby a strip or strap of tape may be attached to a garment by being sewed thereto and stitched 15 along the outer edges leaving a space between the rows of stitching to permit the insertion of a stiffener either while being sewed to the garment or afterward.

The attachment consists essentially of a 20 supporting arm adapted to be attached to the head of the machine and extend upwardly over the head of the machine, and be provided with a series of supporting shafts adapted to carry spools, on which the tape 25 and stiffener to be sewed to the garment are carried.

Carried by pivotal supporting arms attached to the head of the machine and adapted to extend in front of the head 30 immediately below the upper end of the supporting arm on alinement, is a folder which consists of a flattened tube, the lower end being curved and adapted to direct the strip of material also the stiffener to a position 35 immediately in front and very close to the foot and needle of the machine. The upper end of the folder is open and flared and is formed with wings adapted to turn the outer edges of the strip of material inwardly in 40 the course of passing down through the tube to the point of egress.

I attain these objects by the device as illustrated in the accompanying drawings in which;

45 Figure 1 is a perspective view of a sewing machine with the attachment in position; Fig. 2 is a front elevation of the folder; Fig. 3 is a side elevation of the folder; Fig. 4 is a detail perspective view of the upper end 50 of the folder, and Figs. 5, 6, and 7, are cross sectional views through the upper end of the folder on line *a—a*, *b—b*, and *c—c*, Fig. 4, respectively.

Like letters refer to like parts throughout the specification and drawings.

a designates a carrying arm preferably consisting of a curved strip of metal adapted to be fastened to the back of the head of a sewing machine and extend upwardly and forwardly. Fastened to the carrying arm 60 and extending at right angles therefrom are supporting shafts *b* on which are mounted rotatable spools *c*, and on the spools are wound the strip of fabric or tape adapted to be stitched to the garment.

In the illustration I have shown two spools carried by the supporting arms, but any number may be carried for different class work. On the outer ends of the supporting shafts are adjusting collars *d* provided with thumb-nuts *e* by which they may be adjusted to the supporting shafts for the purpose of readily removing and replacing the spools.

f designates the folder which consists of a flattened curved tube open at both ends, the upper end *f'* being flared or enlarged and formed with wings *g* in each of its outer edges, being adapted to engage with the outer edges of the strip of fabric or tape and 75 turn the edges inward in the course of passing down through the tube. The wings are formed by a section of the tube being slitted and folded in upon themselves and extend from the upper outer end of the folder, 80 downwardly any convenient depth, a slight interval being left between the wing and the side of the tube, so that a strip of material passing down between the wing and the side of the tube will be directed and creased by 85 engaging with edge of the wing. Extending downwardly from the upper part of the folder and in a position interposed between the two wings, is a flat tongue *h* formed by the slits by which the wings are formed, the 90 purpose of the tongue being to press or hold the strip of tape flat within the tube and provide against buckling as the edges are being turned up by the wings *g*.

Figs. 5, and 6, illustrate the relative position of the combination of the strip, tongue, and folder in the act of turning the edge inward. Fastened to the back of the folder *f* are connecting arms *i* and *j* by which the folder is adjustably attached to the head of the machine. The connecting arms are attached to the head of the machine by thumb-nuts *k* by which they may be adjusted or removed. Formed on the outer face of the folder are a series of guide loops *l* by which 105

110

- the stiffener or interlining may be directed down the outer face of the tube to the point of egress in the bottom of the tube through which the strip of tape or fabric passes.
- 5 Formed through the front face of the folder is an elongated slot *n* by which communication to the interior of the folder may be had for the purpose of getting at the strip of tape or fabric within the folder in the event 10 of it getting twisted or stuck, and also for the purpose of directing it down through the tube when first being connected. The end of the tongue *h* is slit to make the end pliable and also to facilitate the passing of 15 the tape or strip down through the tube in the initial passage through the tube or folder. The upper connecting arm *i* by which the folder is connected to the head of the machine is jointed, and adjustable 20 by a thumb-nut *l*, that the upper or folding end of the folder may be adjusted away from or against the head of the machine to bring it in a proper position below the spool *c*.
- 25 The operation of the device is as follows, the strip of fabric or tape is wound around one of the spools *c* preferably the lower, and the stiffener or interlining the upper. The free end of the fabric or tape is directed 30 downwardly and forced into the flared upper end of the folder, the outer edges engaging between the folding wings *g*, that the edges may be folded over upon themselves in passing down through the out-

let in the lower end of the folder. The free 35 end of the stiffener or interlining passes down through the guide loops *l* and are adapted to engage with the folded strip of fabric at the bottom of the folder and pass under the foot of the machine and needle, 40 by which the strip is stitched along the outer edges, and the stiffener or interlining in between the folded edges of the fabric. The strip or tape and the stiffener or interlining are regulated in passing through the folder 45 by the action of the needle foot and will be drawn in through the folder as required.

What I claim as new and desire to secure by Letters Patent is,

In an attachment for sewing machines, a 50 curved flattened tube, said tube open at either end, the upper end of the said tube being flared or expanded, folding wings formed integral with the inner sides of the flared upper end of the said tube, a flexible 55 slitted tongue formed in between the said folding wings in the said tube, guide loops formed on the outer face of said curved tube, connecting arms formed with the said tube, said connecting arms adapted to adjustably 60 attach said curved tube to the head of the machine, substantially as described.

Signed at Toronto, this 28th day of October, 1909.

DAVID COGHILL.
